UNITED STATES PATENT OFFICE.

ROBERT E. BROWN, OF OLEAN, NEW YORK.

DESIGN FOR A KNIFE.

Application filed February 7, 1928. Serial No. 25,256. Term of patent 14 years.

To all whom it may concern:

Be it known that I, ROBERT E. BROWN, a citizen of the United States of America, residing at Olean, in the county of Cattaraugus and State of New York, have invented a new, original, and ornamental Design for a Knife, of which the following is a specification, reference being had to the accompanying drawing, forming a part hereof.

In the drawing:

Figure 1 is a side view of a knife in open position showing my new design;

Fig. 2 is a back view of the same, and

Fig. 3 is a side view of the closed knife showing the design.

I claim:

The ornamental design for a knife, as shown.

ROBERT E. BROWN. [I.S.]
